UNITED STATES PATENT OFFICE.

GOODRICH Q. LEWIS, OF WHEATON, ILLINOIS, ASSIGNOR TO WILLIAM H. MINER, OF CHAZY, NEW YORK.

HIGH-CAPACITY SPRING-GEAR.

1,288,625.

Specification of Letters Patent. Patented Dec. 24, 1918.

Application filed April 13, 1916. Serial No. 90,843.

To all whom it may concern:

Be it known that I, GOODRICH Q. LEWIS, a citizen of the United States, residing at Wheaton, in the county of Dupage and State of Illinois, have invented a certain new and useful Improvement in High-Capacity Spring-Gears, of which the following is a full, clear, concise, and exact description, reference being had to the accompanying drawings, forming a part of this specification.

This invention relates to improvements in high capacity spring gears.

The object of the invention is to provide a spring gear for railway draft riggings of high capacity, efficient operation, simple arrangement, and few parts which may be cheaply manufactured. The invention furthermore, consists in the improvements in the parts and devices and in the novel combinations of the parts and devices herein shown, described and claimed.

In the drawing forming a part of this specification, Figure 1 is a vertical, longitudinal, sectional view of a draft rigging, showing my improvements in connection therewith. Fig. 2 is a horizontal sectional view of the draft gear illustrated in Fig. 1 and taken substantially on the line 2—2 of Fig. 3. Fig. 3 is a vertical transverse sectional view taken substantially on the line 3—3 of Fig. 2; and Fig. 4 is a perspective view of the yoke-acting member.

Referring to said drawing, 10—10, denote the center or draft sills, the same having secured to their inner faces stop castings A—A. Each of said stop castings A is provided with a pair of upper and lower rear shoulders 11, a pair of upper and lower front shoulders 12, a pair of upper and lower front intermediate shoulders 13, a pair of upper and lower rear intermediate shoulders 14, and corresponding pairs of upper and lower limiting stop shoulders 15, 16, 17 and 18. The castings are provided with suitable counter sinks to receive the rivets by which they are attached to the respective sills. Vertically extending webs 19, 20 and 21 are also provided between the pairs of front limiting stops, intermediate main stops, and rear limiting stops, respectively.

The gear proper comprises tandem arranged, vertical, twin springs 22, 23, 24 and 25, each spring preferably consisting of an

outer heavy coil and an inner nested lighter coil. Eight followers are provided, four upper followers 26—26 and four lower followers 27—27, which coöperate with their respective stops, as will be understood.

The gear is operatively connected to the draw-bar 28 by means of a yoke designated generally by the reference B. The yoke B is preferably in the form of a casting, having a box-like hood or head 29 at its forward end, side walls of said hood being extended as indicated at 30 and slotted as at 31 to receive the coupler key 32. The yoke B also has a horizontal single arm 33 from the upper and lower sides of which extend hollow box like projections or abutments 34 and 35 at the center thereof. At its rear end, the yoke is provided with vertical, upwardly and downwardly extending flanges or abutments 36 and 37, which coöperate with the upper and lower rear followers. As will be understood, the members 34 and 35 form the thimble of the tandem yoke and coöperate with the intermediate followers of the gear, the front followers of the gear abutting the rear wall 38 of the hood. The cross-section of the arm 33 is most clearly shown in Fig. 3 and is provided on its upper face with a concave surface 39, and on its lower face with a similar concave surface 40, said surfaces 39 and 40 forming seats for the upper and lower springs respectively. The parts are supported by means of saddle plates 41—41, detachably bolted to the lower flanges of the center sills 10.

In draft, it is apparent that the yoke B will move forwardly with the draw bar, and thereby move the rear followers and rear intermediate followers forwardly. In buff, the draw-bar will force the yoke B rearwardly, which in turn will force the front followers and rear intermediate followers rearwardly, the compression of the springs and movement of the yoke being limited by the limiting stops, as will be understood.

From the preceding description it will be seen that the gear which I have provided is of unusually high capacity, is compactly arranged, and the parts may be readily assembled and disassembled whenever desired. It will also be seen that the lower sets of springs can be removed without disturbing the draw bar and yoke connection, by merely taking

off the tie plates 41, thereby minimizing the weight of the parts which have to be handled at any one time.

I claim:

1. In a spring draft gear, the combination with tandem twin arranged springs and coöperable followers, of means for operatively connecting said springs and followers with a draw-bar, some of said springs being removable from below without disturbing the yoke and draw bar connection, said means including a centrally disposed horizontal column member, said member having integral abutments at each end and also at the center for engagement with the followers and arranged to actuate the gear in tandem.

2. As an article of manufacture, a yoke for draft rigging having a single horizontal arm with integral abutments extending from opposite sides thereof, at both ends, and also at the center, the horizontal arm being adapted to extend in the center line of the draft rigging.

3. In a draft rigging for railway cars, the combination with stop castings each provided with an upper and a lower set of tandem arranged stops, of an upper set of tandem arranged springs and followers coöperable with the upper set of stops on the castings, and a lower set of tandem arranged springs and followers coöperable with the lower sets of stops on said castings.

4. In a draft rigging for railway cars, the combination with stop castings, each provided with sets of tandem arranged shoulders, of an upper set of tandem arranged springs and followers, a lower set of tandem

arranged springs and followers, and a horizontally extending yoke between the upper and lower sets of followers, said yoke having upper and lower end and central abutments for actuating the followers.

5. In a spring draft gear, the combination with two sets of twin arranged springs, one set being disposed behind the other in tandem formation, of an independent follower coöperable with each end of each spring, stop castings having shoulders coöperable with said followers, and means for operatively connecting said springs and followers with a draw bar, each of the lower springs and associated followers being independently removable from below and without disturbing the other elements of the gear.

6. In a draft rigging, the combination with stop members having upper and lower sets of stops, of a set of vertical twin arranged springs, independent sets of followers for each of said springs and coöperable with said upper and lower sets of stops, a yoke adapted to operatively connect said springs and followers with a draw bar, said yoke having a horizontally and centrally disposed arm extending between the upper and lower sets of followers, means for supporting the lower spring and followers, said yoke being supported by said lower set of spring and followers and the yoke in turn supporting the upper set of spring and followers.

In witness that I claim the foregoing I have hereunto subscribed my name this 22nd day of March, 1916.

GOODRICH Q. LEWIS.
